UNITED STATES PATENT OFFICE.

HENRY S. GRIFFIN, OF PIQUA, OHIO.

DRILL-LOCK.

1,176,215.

Specification of Letters Patent. Patented Mar. 21, 1916.

Application filed October 11, 1915. Serial No. 55,259.

To all whom it may concern:

Be it known that I, HENRY S. GRIFFIN, a citizen of the United States, residing at Piqua, in the county of Miami and State 5 of Ohio, have invented a new and useful Drill-Lock, of which the following is a specification.

The device forming the subject matter 10 of this application is a drill lock, adapted to hold against rotation with respect to a drill rod, a drill which has a threaded connection with the drill rod.

The invention aims to provide a locking 15 member of novel form, movable with respect to the drill rod and adapted to engage the drill, and to provide novel means whereby a movement of the locking member may be prevented.

Another object of the invention is to 20 provide a structure of the type above described in which the locking parts will not deteriorate due to rust or otherwise.

It is within the province of the disclosure to improve generally and to enhance the 25 utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made 30 within the scope of what is claimed, without departing from the spirit of the invention.

In the accompanying drawing:—Figure 1 shows the invention in side elevation, parts being broken away, the locking mechanism being in the positions assumed when the drill is upheld to the drill rod; Fig. 2 is a cross section on the line 2—2 of Fig. 1; Fig. 3 is a fragmental longitudinal section of the drill rod, showing the locking mechanism in the position it will occupy while the drill is being threaded into the drill rod; Fig. 4 is a fragmental cross section taken on the line 4—4 of Fig. 3.

In the accompanying drawings, the numeral 1 indicates a drill holder, preferably in the form of a rod, and the numeral 2 designates a drill of any desired form. The drill 2 is provided with an upstanding threaded shank 3 adapted to coöperate with 55 a threaded recess 4 formed in the lower end of the drill rod, the shank 3 defining a

transverse shoulder 5 in the drill 2 about the shank. In the shoulder 5, to one side of the threaded shank 3 a recess 6 is formed and in the lower end of the drill rod 1 60 to one side of the threaded recess 4, an opening 7 is formed, the opening 7 being adapted to be alined vertically with the seat 6 under conditions which will be pointed out hereinafter. Formed in the drill rod 1 and communicating with the opening 7 in the lower end of the drill rod is an upright passage 8, the upper end of which is threaded as indicated at 9. At its upper end, the passage 8 communicates with a lateral recess 10 70 formed in the drill rod 1.

Movable longitudinally for adjustment in the passage 8 is a locking member 11 preferably in the form of a rod, the upper extremity of the locking member 11 being 75 threaded as shown at 12 so as to coöperate with the threaded portion 9 of the passage 8. In the upper end of the locking rod 11, a screw driver kerf 14 is formed, the kerf 14 being accessible by way of the recess 10 in the drill rod 1.

The invention comprises a latch block 15 conforming to the transverse contour of the opening 7 in the lower end of the drill 1 and to the cross sectional contour of the seat 6 in the upper end of the drill 2. The lower end of the rod 11 is journaled for rotation in the latch block 15 and is held thereto for rotation by means of a screw 16 threaded into the lower end of the rod, the screw 16 having a screw driver kerf 17.

The invention comprises a plug 18 adapted to be threaded into the upper end 9 of the passage 8 in the drill 1, under circumstances which will be pointed out hereinafter, the plug 18 being provided with a screw driver kerf 19 which is accessible through the recess 10 in the drill rod 1. Upon the exterior surfaces of the drill rod 1 and the drill 2, marks 20 are formed.

In practical operation, the plug 18 is threaded out of the end 9 of the passage 8. Then a screw driver is applied to the kerf 17 of the screw 16, the rod 11 being rotated, and the latter turning in the latch block 15. When the rod 11 is rotated, the rod moves upwardly into the position shown in Fig. 3, because the upper end 12 of the rod is threaded into the portion 9 of the passage 8. Ultimately, the lower face of the latch block 15 is disposed flush with the lower face of the drill rod 1 as shown in Fig. 3 of the

drawings. When the parts are thus arranged, the shank 3 of the drill 2 may be threaded into the recess 4 in the drill rod 1. Relative rotation between the drill rod 1 and the drill 2 is continued until the marks 20 on the drill and the drill rod are lined up vertically. When the marks 20 are lined up vertically, the seat 6 in the drill 2 is lined up vertically with the opening 7 in the drill rod 1. Then, through the recess 10 in the drill rod 1, a screw driver is applied to the kerf 14 of the rod 11 and the latter is moved downwardly, because it is threaded as shown at 12 into the part 9 of the passage 8. As the rod 11 moves downwardly, it rotates in the latch block 15 and carries the latter downwardly until the latch block finally is engaged in the seat 6 as shown in Fig. 1. Then, the threaded plug 18 is mounted in the threaded upper end 9 of the passage 8 and engages the upper end of the rod 11 to lock the same against rotation. When the parts are disposed as above described, it will be obvious that relative rotary movement to any appreciable extent between the drill rod 1 and the drill 2 will be impossible. If desired, however, a slight relative rotation between the drill and the drill rod may be brought about, so that the marks 20 are disposed slightly out of the position of alinement shown in Fig. 1, the latch block 15 under such circumstances, being firmly gripped by the drill 2.

The threaded plug 18, the rod 11 and the latch block 15 ordinarily are made out of brass or some similar metal which will not rust or deteriorate rapidly.

Having thus described the invention, what is claimed is:—

40 1. In a device of the class described, a

Copies of this patent may be obtained for five cents each, by addressing the "Commissioner of Patents, Washington, D. C."

drill and a drill holder having a threaded connection, the drill having a seat; a screw threaded into the drill holder and disposed longitudinally thereof; and a latch block in which the screw is journaled, the latch block being movable by the screw to engage with the seat.

2. In a device of the class described, a drill and a drill holder having a threaded connection, the drill holder having a seat; a screw threaded into the drill holder and provided with means for engaging the seat; and a second screw disposed coaxially with the first specified screw and threaded into the drill holder, the second screw being adapted to coact with the first specified screw to prevent a rotation thereof.

3. In a device of the class described, a drill and a drill holder having a threaded connection, the drill having a seat; a primary screw disposed longitudinally of the drill holder and threaded thereinto; a latch block in which the screw is journaled, the latch block being movable under the action of the screw to engage with the seat; and a second screw disposed axially with respect to the primary screw and threaded into the drill holder, the second screw being adapted to co-operate with the primary screw to prevent a longitudinal movement thereof, and to prevent a retraction of the latch block from the seat.

In testimony that I claim the foregoing as my own, I have hereto affixed my signature in the presence of two witnesses.

HENRY S. GRIFFIN.
